(57) **CLAIM**

The ornamental design for a motor vehicle, toy replica and/or other replica, as shown and described.

DESCRIPTION

FIG. 1 is a front and right side perspective view of a motor vehicle, toy replica and/or other replica showing our new design.

FIG. 2 is a rear and left side perspective view thereof;

FIG. 3 is a front view thereof;

FIG. 4 is a rear view thereof;

FIG. 5 is a left side view thereof;

FIG. 6 is a right side view thereof; and,

FIG. 7 is a top view thereof.

The wheels and lights of the motor vehicle shown throughout the drawing views in a de-emphasized and faded out halftone manner are for environmental and illustrative purposes and form no part of the claimed design.

1 Claim, 4 Drawing Sheets
